UNITED STATES PATENT OFFICE

2,493,826

FORM FOR BUILDING CEMENTITIOUS WALLS

Floyd L. Oelfke and Richard L. Horstman,
Kansas City, Mo.

Application June 9, 1947, Serial No. 753,460

3 Claims. (Cl. 25—131)

1

This invention has to do with the field of building and construction and more specifically to formation of cementitious walls or the like and has for its primary aim the provision of a form or mold adapted to receive material from which said wall is made and hold the same in place.

The most important object of this invention is the provision of a building form having a pair of spaced apart opposed frame members, each made from a plurality of sections and having a number of spacers interconnecting the frame members through the medium of a releasable pin, the latter of which also serves in holding together the said sections.

Another important object of this invention is to provide a form having a number of panels lining the proximal innermost faces of the aforesaid frame members and temporarily secured to the latter through the use of tie members which may be readily severed when the form is to be removed.

A further object of this invention is the provision of a building form for cementitious walls or the like wherein the above mentioned lining panels may be used if desired as a finishing surface when the wall is completed and after the frame portion of the form is removed.

Other objects of this invention relate to the manner in which a thimble-like plug is utilized to hold the panels upon the frame members to the end that a smooth surface is made possible after removal of the form by simply filling in the opening left by the removed plug; and the particular way in which the frame sections of the form are made to the end that same may be re-used from time to time.

Many minor objects will be made clear during the course of the following specification, reference being had to the accompanying drawing, wherein:

Fig. 1 is a fragmentary perspective view of building structure in the form of a mold made in accordance with our present invention.

Fig. 2 is a vertical cross sectional view through the building structure and wall shown in Fig. 1; and

Fig. 3 is an enlarged fragmentary cross sectional view showing the manner in which the lining panels are mounted upon the frame sections.

In the drawing, the numeral 10 designates broadly a wall made from cementitious material or the like to be constructed through use of the

2

building form about to be described. This building form includes a pair of spaced apart frame members 12 and 14, each of which includes a plurality of sections 16. These sections 16 are disposed in side-by-side upright relationship and each comprise a pair of spaced apart vertical bars 18 and a plurality of interconnecting cross members 20. These cross members 20 are spaced apart and secured to the vertical bars 18 by fusing or other similar means of attachment.

The frame members 12 and 14 each formed by their respective sections 16, are held in spaced apart opposed relationship by a number of spacers 22. These spacers 22 span the distance between the opposed sections 16 of frames 12 and 14 respectively and are held in place through the medium of pins 24. These pins 24 also serve to releasably hold the sections 16 of each of the frame members 12 and 14 together in side-by-side relationship. In other words, the spacers 22 each have an opening at each end thereof and the pins 24 pass through such openings and through aligned openings in the vertical members 18 of the sections 16, all as illustrated in Fig. 1 of the drawing.

A number of panels 26 and 28 line the normally innermost faces of sections 12 and 14 respectively. A number of tie members 25 formed in the manner illustrated in Fig. 3 serve to hold these panels 26 and 28 on their respective sections 12 and 14. These tie members 25 are preferably formed from wire or other easily cut material and have one end thereof looped over the cross members 20 of the sections 16 as at 27.

Tie members 25 extend through openings 29 formed in the panels 26 and 28 and project inwardly to a laterally turned end 30. Each of the tie members 25 has a thimble-like plug 32 threaded thereon between the end 30 thereof and the proximal innermost face of the respective panels 26 and 28.

It is readily seen that when the form is made as above described, the panels 26 and 28 thereof are held in spaced apart relationship to receive the material which forms the wall 10. When this material has dried and set, removal of the form is accomplished through the following steps:

The pins 24 holding the sections 16 upon the spacers 22 are all removed and the tie members 25 are either clipped adjacent the outermost face of the panel 26 or 28 or the looped portion 27 thereof bent outwardly to permit removal of the sections 16 of frames 12 and 14.

When these steps have been completed, the panels 28 may be easily removed and the plugs

32 slipped from the tie members 25. These tie members 25 are then cut within the cavity of wall 10 left because of removal of plugs 32. A portion of the tie members 25 will then project into such cavity and when these cavities are filled, such projecting end of the tie member 25 will serve to support such filling. It is, of course, notable that the end 30 of the tie member 25 remains in the wall 10 after the form is removed.

The panel 26 which is disposed on the normally innermost face of wall 10 may either be removed in the same manner as just described with respect to the panel 28 or allowed to remain in place as an insulation board for receiving paper, paint or plaster, as desired. If the frame members 12 and 14 are removed by turning the looped end 27 of tie members 25 outwardly, then these members 25 are afterwards cut adjacent the outermost face of the panels 26 to present a smooth surface. In the event that this panel 26 is allowed to remain in place for subsequent use as insulation, it is desirable to place a number of nails or the like 34 thereinto to project into the wall 10 prior to the pouring of the same.

The panels 28 may be made from any suitable material such as metal sheets if desired but inasmuch as the panels 26 are preferably to be used for the additional purpose of insulation, it is necessary that the innermost face thereof have a coating of water-proofing material spread thereon before the concrete is poured for the wall 10.

After the section 16 of frame members 12 and 14 are removed and after the panels 28 are also taken from the outermost face of the wall 10, the spacers 22 will have their ends projecting from each of the faces of wall 10. The final step, therefore, is to cut these ends smooth with the proximal faces of the wall 10 or if desired, these spacers 22 may have lines of weakness formed therein to the end that the simple bending action applied to these projecting ends will cause the same to break and present a smooth surface to the well.

Wall 10 is provided with the usual strengthening members 36 as illustrated in Figs 1 and 2.

It is to be noted that through use of the form shown in Figs. 1 to 3 inclusive, it is not necessary that the wall 10 have straight inner and outermost faces. If desired, as shown in Figs. 1 and 2, the lowermost portion of wall 10 or the foundation for the building to be constructed, may be wider than the uppermost portion thereof. This variance in the width of the wall 10 is accomplished by simply varying the length of the spacers 22.

It is apparent that through use of the form just described, a wall of cementitious material or the like may be quickly and easily formed and after the same has set, the frame work can be removed in a minimum amount of time. This form is relatively light and inexpensively manufactured.

It is understood that many adaptations may be made different from those above described and those made possible are contemplated hereby. It

is, therefore, desired to be limited only by the spirit of this invention and scope of the appended claims.

Having thus described the invention, what is claimed as new and desired to be secured by Letters Patent is:

1. A form for building cementitious walls or the like comprising a pair of spaced apart, opposed frame members; a plurality of spacers 10 spanning the distance between said frame members; panels secured to and covering the proximal faces of each of said frame members respectively; and means for releasably attaching said spacers to said frame members, said frame members each being sectional, said means serving to releasably interconnect said sections of the frame members, said sections of the frame members each including a pair of spaced vertical bars and a plurality of cross members interconnecting the bars, said 15 panels having a plurality of tie members securing the same to each of said cross members of proximal frame sections, one end of each tie member extending through said panels and beyond the face thereof opposite to the corresponding cross members, and a plug on each tie member disposed on said face of the panels for holding the latter against respective frame sections.

2. A form for building cementitious walls comprising a pair of opposed frames; a panel for each 30 frame respectively and covering proximal faces of the frame; a plurality of spacers releasably interconnecting the frames and passing through said panels; and a number of wires extending through the panels, one end of all wires being looped over parts of the frame, the opposite ends of the wires being extended into the space between the opposed panels.

3. A form for building cementitious walls comprising a pair of opposed frames; a panel for each 40 frame respectively and covering proximal faces of the frames; a plurality of spaces releasably interconnecting the frames and passing through said panels; a number of wires extending through the panels, one end of all wires being looped over parts of the frame, the opposite end of the wires extending inwardly into wall forming material between the panels; and removable thimble threaded on all wires respectively adjacent said 45 opposite ends thereof bearing against the inner face of the proximal panels whereby to form a cavity within the wall when the frames, the panels and said thimbles are removed.
